MAGAZINE BUFFER.

Application filed June 11, 1927. Serial No. 198,079.

This invention relates to buffers or applicators of the magazine or reservoir type which are designed to contain a substance to be applied and subsequently spread or worked over a surface to polish or give the desired finish thereto, the principal use residing in the employment of the device as a combined container for nail polish and as an applicator and buffer therefor.

10 The invention primarily comprehends a magazine buffer and applicator including a buffer section and a magazine applicator section, the latter having a discharge port adapted to be respectively closed and opened by 15 relative movement between the sections and which port when opened being designed to permit of the discharge of a quantity of the contents of the magazine section on to the nail or other surface to be polished, the buffer 20 section being subsequently employed for spreading the contents and polishing or buffing the nail or other surface.

More specifically the invention comprehends telescopically associated buffer and 25 magazine sections, said sections each having a discharge port adapted to be disposed respectively in and out of registry upon relative movement between the sections.

The invention furthermore comprehends 30 in a magazine buffer and applicator, means for arranging and holding the buffer material or cloth over the buffer section in such a manner as to present a polishing edge in addition to the polishing surface.

35 The invention furthermore comprehends in a buffer section for a magazine buffer and applicator, means for connecting the buffer material and pad to the buffer section body.

Other objects reside in the comparative 40 simplicity of construction, the economy with which the same may be produced and the general efficiency derived therefrom.

With the above recited and other objects in view, reference is had to the following description and accompanying drawings in which there are exhibited certain examples or embodiments of the invention, while the appended claims define the actual scope of the invention.

50 In the drawings—

Figure 1 is a perspective view of a combined buffer and applicator constructed in accordance with the invention;

Fig. 2 is a sectional view taken approximately on the line 2—2 of Fig. 1;

Fig. 3 is a sectional view taken approximately on the line 3—3 of Fig. 2;

Fig. 4 is a plan view of a modified adaptation of the invention;

Fig. 5 is an inverted plan view of the buffer 60 section removed from the magazine section;

Fig. 6 is a longitudinal sectional view taken approximately on the line 6—6 of Fig. 4;

Fig. 7 is an inverted plan view of the buffer 65 pad detached from the buffer section;

Fig. 8 is a sectional view taken approximately on the line 8—8 of Fig. 5;

Fig. 9 is an end view of the form illustrated in Fig. 4, with the discharge port closed;

Fig. 10 is a similar view with the discharge 70 port opened.

Referring to the drawings by characters of reference and particularly to the form of the invention illustrated in Figs. 1, 2 and 3, the magazine buffer and applicator includes 75 a magazine section in the form of a cylindrical body 16 having a closed bottom 17 and an open top. The cylinder or annular wall of the body is provided with an outpressed annular bead or shoulder 18 spaced axially from the upper open end. A discharge port or opening 19 is formed in the cylindrical body 16 at a point slightly spaced above the bead 18. The buffer section includes a cylindrical wall 20 having a concavo-convex upper 80 end 21, the wall 20 being telescopically arranged over the upper portion of the cylindrical body 16 and extending between the bead and the upper open end thereof. The cylindrical wall 20 of the buffer section is 85 provided with a discharge port or opening 22 which upon relative turning movement of the sections, is adapted to be disposed respectively in and out of registry with the discharge port or opening 19 of the section 16. 90

In order to limit the relative rotary movement between the sections and to provide a stopping point at which the ports or openings 19 and 22 are disposed in registry, the cylindrical wall 16 is provided with an outstruck teat 23, while the cylindrical wall 20 is formed with an outstruck grooved portion or channel 24. The teat and groove also serve to retain the sections in associated relation against accidental displacement. The 100 upper concavo-convex end wall 21 of the buffer section is covered with a buffer material 25, such as chamois, between which and the wall 21 a suitable padding 26 is arranged.

The marginal edge of the covering 25 is 110

turned downwardly over the cylindrical wall 20 and is held in place between an annulus or ring 27 and an outstruck marginal bead 28 formed on the cylindrical wall 20. The annulus or ring 27 is of arcuate or concavo-convex configuration in cross-section to effectually grip and maintain the marginal edge of the covering 25. Between the retaining ring and the upper surface of the covering 25, an annular polishing or operating surface 29 is provided, which permits of the use of the buffer on surfaces or places which would otherwise be inaccessible by the upper surface alone.

15 In use, the powdered polishing substance 30 within the magazine section, is dispensed by turning the buffer section with respect to the magazine section until the ports 19 and 20 are in registry. The desired quantity 20 of the contents 30 is then discharged onto the surface to be polished, after which the sections are rotated relatively until the ports are out of registry, and the magazine section is then employed as a handle for manipulating the buffing surface over the surface to be polished.

30 In the form of the invention illustrated in Figs. 4 to 9, inclusive, 31 designates a substantially continuous elliptical or oval wall 39 of a magazine section, which is provided with a closed bottom 32. In this form of the invention, the magazine section includes a closure member including a continuous substantially elliptical or oval wall 33 and a top wall 34, the former adapted to frictionally fit within the wall 31 and the latter wall, 34, combining therewith and with the bottom wall 32, to define a compartment for receiving the polishing substance. The upper 40 wall 34 is provided with a central depression 35 having a cross element 36 defining a handle for facilitating the removal of the closure member to re-fill the magazine section. The wall 33 of the closure member and the wall 31 of the body of the magazine section are provided with registering ports or 45 openings 37 and 38 constituting means for discharging or dispensing the contents of the magazine section. The wall 31 is cut 50 away or rabbeted at 39 on its outer surface adjacent the upper end, to telescopically receive thereover, the continuous marginal wall 40 of a buffer section. Intermediate its upper and lower open ends, the wall 40 is provided 55 with a horizontal wall 41 having spaced slots 42.

60 A buffing means including a pair of superimposed plates 43 and 44, a buffer material 45 and a pad 46, is provided. The marginal portion 47 of the buffer material 45 is turned under the plate 44 and is suitably secured in place by a drawstring 48. The buffing means is of a size and configuration to snugly fit within the wall 40 above the partition wall 65 41. The plate 44 is provided with downward-

ly projecting lugs 49 spaced apart an appropriate distance to project through the slots 42 of the partition wall 41. The lugs 49 are each laterally slotted at 50 from the side edges to receive the opposite ends 51 of the lock bar 52, which is centrally pivoted at 53 for turning movement on the under side of the partition wall 41. This detachably connects the buffing means with the buffer section and permits renewal or replacement of the buffer material 45. The wall 40 of the buffer section is provided with an aperture or port 54 at one of its ends and is designed upon removal and replacement of the buffer section on the magazine section, to respectively bring the port into and out of registry with the aligned openings or ports 37 and 38 of the buffer section as illustrated in Figs. 9 and 10, so that the contents of the magazine section may be dispensed.

85 What is claimed is:

1. A magazine buffer and applicator, including a buffer section and a magazine section having a discharge port adapted to be respectively closed and opened by relative movement between the sections, the said buffer section including a continuous wall and a closed end, the continuous wall having a marginal bead spaced from the end wall, a buffer material arranged over the end wall and having a marginal portion extending downwardly over the continuous wall and over the bead, and a clamping ring engaging over the bead and clamping the marginal portion of the buffer material in place.
